OIL BURNER AND FIRE CONTROL DEVICE

Jackson G. Gilmore and William H. Gilmore,
Columbus, Ohio; William H. Gilmore, execu-
tor of said Jackson G. Gilmore, deceased

Application March 14, 1949, Serial No. 81,276

12 Claims. (Cl. 158—91)

1

This invention relates to improvements in oil burners and fire control devices and has for an object to equip the more or less conventional pot type oil burner now in widespread use with means to control the gases for combustion and the fire resulting from such combustion at low or pilot fire stage and also to provide means to control the flow of gases of combustion in such wise as to produce an efficient and satisfactory intermediate and/or high fire whereby marked economy may be obtained in low fire operation with a low fuel consumption and clean fire whereby efficient, clean, and generally satisfactory intermediate and high fires may be obtained by increasing the fuel supply.

Another object is to provide a control device which may be readily added to existing pot type burners now in operation without necessity for removal of such burners from their environment. These and other objects will be more fully set forth and described in the accompanying specification and illustrated in the accompanying drawing, in which:

Figure 1 is a vertical section through the pot type burner having our control devices incorporated therein;

Fig. 2 is a horizontal section taken along the line 2—2 of Fig. 1;

Fig. 3 is a bottom view taken along the line 3—3 of Fig. 1;

Fig. 4 is a detailed section along the line 4—4 of Fig. 1;

Fig. 5 is a fragmentary sectional view of a modified form of control member;

Fig. 6 is an elevation in perspective of a modified form of shield member; and

Fig. 7 is a vertical section of a complete burner illustrating the modified elements of Figs. 5 and 6 in assembled relation.

Like numerals refer to like elements throughout the drawing in which 10 indicates the oil burner pot generally, the same being provided with a closed bottom 11 and an enclosing side wall 12 open at the top and outwardly peripherally flanged at the top from the flange 13. An oil inlet 15 is provided at the bottom of the wall 10 and communicates with the interior of the pot in alignment with a shallow, radial trough 16a. As illustrated, the pot may be made in two sections, the bottom section being provided with a flange 11b overlapping the bottom of the side wall 12 and secured tightly thereto as by welding or the like. The side wall 12 is provided with a plurality of rows of air holes preferably arranged horizontally as illustrated in Fig. 1 of the drawings. The lowermost row of such holes designated by numeral 12a is preferably, but not necessarily, inclined downwardly as illustrated. When the pot is formed of sheet metal, it is customary to obtain the inclination of such holes by

5 a distortion of the metal with a pointed tool, or the like, thereby insuring that inflowing jets of air will be directed downwardly toward the bottom of the pot. Located above and spaced from the air holes 12a is a row of air holes 12b. The member or collar 25 is so located when in operative position that the bottom 25d is slightly above the plane of the primary air holes 12a. This, together with the downward inclination of 10 such air holes, is calculated to prevent or substantially prevent impact of primary air against the member 25 during low or pilot fire operation. Similarly, there are provided additional vertically spaced horizontal rows of holes 12c and 12d. At the top is provided a row of what are frequently termed secondary air holes 12e, tilted upwardly, as illustrated in Fig. 1 of the drawings. Overlying and mounted upon the flange 13 of the pot is the horizontal ring 16, centrally apertured at 16a to provide an outlet for the gases of combustion and such flames as may be incidental thereto at high fire.

15 The pot is mounted in any suitable manner, as in a spaced surrounding casing or drum 18 constructed for ingress of adequate air for flow through the air holes in the pot side wall 12 for mixture with fuel gases generated therein. The ring 16 serves to close the space between the pot and the casing 18 at the top row as illustrated in Fig. 1.

20 Located in the pot with its outer periphery in proximity to the side wall 12 is a ring 20, generally termed a "fire ring," supported, in the embodiment shown, upon pins 21 projecting inwardly from said side wall. This ring is provided with a central opening 20a and, in the form shown, is inclined upwardly and inwardly from its outer edge. The ring is located above the lowermost air holes 12a and beneath others of the air holes. As is well known, air flowing through the holes 12a is sufficient in amount to support combustion of a limited oil supply for low or pilot fire while the other air holes supply air for the support of combustion of the generated oil gas at intermediate and high fires although it is optional with the user or installer whether there be provision for an intermediate fire or whether the change is direct from low or pilot fire to high fire which occurs at and above the ring 16. Mounted in the opening in the ring 20 is the member 25 open at the top and having a side wall or collar portion 25a depending from the ring 20 and provided with ports 25b and an outwardly directed flange 25c at the top which rests upon the upper side of the ring 20. It is desirable if not essential that there be a tight fit or sealing means between the flange and the collar 20 to prevent leakage of gas or air therebetween.

25 The member 25 is provided with a bottom 25d

extending across the collar at its bottom. This bottom is centrally apertured at 25e and is provided with a bent or struck-up portion 25f at one side, the same being inclined upwardly and outwardly above the resultant aperture 25g. This portion 25f is located when the unit is in assembled condition so as to direct heat upon the incoming oil at or adjacent its point of entry whereby volatilization of a small amount of oil used for the pilot fire is enhanced, thereby contributing to the efficiency and economy of the burner at such pilot fire stage. For control of the gases for intermediate and/or high fire, we provide a shield generally indicated by numeral 28, the same comprising a top plate-like portion 28a with a central aperture 28b and with deflector portions 28c shown in the embodiment illustrated as generally segmental in shape and inclined upwardly and outwardly from the central portion of the plate 28a. These deflectors overlie the resultant ports 28d and serve to direct gases flowing upwardly therethrough outwardly toward the pot side wall for better mixture of such gases with the inflowing jets of air at intermediate and high fires. At the same time, these deflectors serve to shield or contribute to the shielding of the oil in the bottom of the pot from the radiant heat of the flame of combustion. The openings 25e and 28b are in general alignment and permit easy access to the bottom of the burner with a torch or other lighting means for initial ignition of the oil in the burner.

The shielding plate 28a is provided with downwardly extending legs 28e which are mounted upon the flange 25c of the member 25, being provided with pins 28f seating in suitable pinholes or apertures in such flange and in the ring 20 thus insuring proper location or positioning of the shielding member relative to the member 25 and the ring 20.

With oil supplied in sufficient amount and gas generated in sufficient volume for high fire, visible combustion will not occur, due to insufficient supply of air, until the jets from the air holes 12e are encountered by the upwardly flowing gases 45 whereupon, the proportion between such gases and the so-called secondary air being properly maintained, a desirable and satisfactory high fire will result and the same will be largely or wholly above the ring 16 which serves to compact the 50 gases and resultant fire for more efficient combustion and heating as is well known in the art.

It is our belief that by restraining the flow of gases from the bottom of the pot at low fuel supply by means of the ring 20, member 25 and the shielding member 28, while permitting restrained flow inwardly of the ports 25b, we are able to compact such gases as are generated and are mixed with air flowing through the primary air holes 12a in such wise as to insure efficient combustion at very low fuel supply while permitting a quick transition from low fire to intermediate fire or directly to high fire when the demand for heat arises. At the same time, the area of the holes 25b is sufficient to permit the flow of the 65 requisite volume of gases to support intermediate and/or high fire when demanded. Undoubtedly, after starting of our burner when it has reached normal operation, additional heat is radiated from the ring 20 and the control member 25, particularly the bottom 25d thereof, which contributes to the volatilization of the inflowing fuel oil.

The reflector 25f of member 25 directs heat upon the inflowing oil adjacent its point of entry

into the pot and thereby contributes to its quicker volatilization, as stated, and thus contributes to the maintenance of proper combustion at low or pilot fire. It is our aim to protect the oil supplied to the burner at intermediate or high fire stages to a substantial degree from radiant heat from the flame or flames above the ring 25c, thereby avoiding undesirable cracking of the oil or oil gases at such stages of fire which otherwise would occur and which would lead to the deposit of objectionable carbon in the pot. The bottom plate 25d also shields the incoming oil to an appreciable degree at least from any flames or visible combustion occurring inside of the collar 25a as at low fire. Heat for vaporization, at intermediate and high fires, is obtained in substantial amount, at least, by the conducted heat flowing through the pot side wall and bottom.

Since there are many outstanding installations of pot type burners unable to handle satisfactorily the catalytic blend fuel oil so largely produced at the present time, our burner is designed to handle such oil and has demonstrated its ability so to do while operating satisfactorily at very low fuel supply for pilot fire which is also highly desirable, as is well known to those familiar with the art.

To extend the benefits of our invention to users of such outstanding installations, we have constructed our member 25 and shield 28 in such manner that they may be readily inserted in and mounted upon the fire ring in the majority of present installations. We find it desirable, however, to provide for positioning of these members as illustrated in the drawings and in the event a flat ring 20 is encountered, it is necessary or desirable to provide a flange or ring or some equivalent means around the aperture 20a in the ring 20 and extending thereabove to receive the flange 25c.

In a concrete embodiment of our invention in an oil burner, the following important dimensions were utilized. This being what is known as an 8 inch burner in the trade, the pot is of approximately 8 inches in diameter. The other important dimensions are as follows:

Outer diameter of ring 20	7 $\frac{1}{2}$ inches.
Diameter of ring aperture 20a	4 $\frac{1}{2}$ inches.
Approximate height of the burner pot	7 $\frac{1}{8}$ inches.
Row of air holes 12a above the bottom of the pot	2 $\frac{3}{8}$ inches.
Distance between air holes 12a and 12b	1 $\frac{1}{8}$ inches.
Distance between air holes 12b and 12c	1 $\frac{1}{8}$ inches.
Distance between air holes 12c and 12d	1 $\frac{1}{8}$ inches.
Distance between air holes 12d and 12e	1 inch.
Diameter of opening at the top of control member 25	4 $\frac{1}{2}$ inches.
Ports 25b, 18 in number—diameter	$\frac{5}{8}$ inch.
Diameter of hole 25e	1 $\frac{1}{4}$ inches.
22 air holes 12a	Each .0960 inch.
22 air holes 12b	Each .0960 inch.
21 air holes 12c	Each .0960 inch.
21 air holes 12d	Each .0960 inch.
100 air holes 12e	Each .120 inch.

It is to be understood that different dimensions, particularly of air holes, etc., are required for different size burners.

Where it is considered desirable, the shielding element 28 may be omitted as for a continuous

low fire for industrial or other uses and in such cases reasonably satisfactory high fire may be obtained although not of the character and quality obtained with such shielding unit. We also find that the shielding element may be omitted in smaller sized burners without detriment to the operation.

In Fig. 5 we have illustrated a modified form of control member generally similar to the form illustrated in Figs. 1 and 3, for example, except that we have substituted a curved portion of the collar indicated at 125a constructed to direct heat beyond the oil flowing into the pot, in lieu of the reflector member 25f of the forms shown in Figs. 1 and 3.

In Fig. 6 we have illustrated a modified form of shield generally indicated by the numeral 128 and having an inverted tapered deflector portion 128a slightly concaved externally, as illustrated, and provided with downwardly directed and outwardly extended legs constructed and arranged to rest upon the ring 20 to deflect the upwardly flowing gases upwardly toward the side wall of the burner while shielding the bottom of the pot to a large extent from the radiant heat of any flame or visible combustion above such deflector.

In Fig. 7 is illustrated the complete assembly of the modified control member 125 and modified shield 128 in position in an oil burner.

While we have illustrated and described one embodiment of our invention, it is to be understood that we do not wish to be restricted to the specific details thereof except as the appended claims may be so limited when properly construed.

What we claim is:

1. An oil burner comprising a pot having a bottom, an enclosing side wall, and open at the top, a plurality of rows of air holes in said side wall, a centrally apertured ring in said pot above some of said air holes, means to support said ring, a fire-control member mounted in the aperture of said ring and having a collar portion depending therebelow, said collar portion being provided with ports below said ring and with an opening at the top, said control member being provided with a transverse bottom extending across said collar portion, said transverse bottom being provided with an aperture therethrough and reflecting means overlying said aperture, positioned to reflect heat on oil flowing into said pot, and means to supply oil to said pot.

2. An oil burner comprising a pot having a bottom, an enclosing side wall, and open at the top, a plurality of rows of air holes in said side wall, a centrally apertured ring in said pot above some of said air holes, means to support said ring, a fire-control member mounted in the aperture of said ring and having a collar portion depending therebelow, said collar portion being provided with ports below said ring and with an opening at the top, said control member being provided with a transverse bottom extending across said collar portion, said bottom portion being provided with a struck-up reflector and an opening therebeneath, said reflector being inclined and positioned to reflect heat upon oil flowing into said pot adjacent its point of entrance, and means to supply oil to said pot.

3. An oil burner comprising a pot having a bottom, an enclosing side wall, and open at the top, a plurality of rows of air holes in said side wall, a centrally apertured ring in said pot above some of said air holes, means to support said ring, a fire-control member mounted in the aper-

ture of said ring and having a collar portion depending therebelow, said collar portion being provided with ports below said ring and with an opening at the top, said control member being provided with a transverse bottom extending across said collar portion, said transverse bottom being provided with an aperture therethrough and a reflecting means overlying said aperture and positioned to reflect heat on oil flowing into said pot, said bottom portion being further provided with a central opening therethrough, and means to supply oil to said pot.

4. An oil burner comprising a pot having a bottom and an enclosing side wall open at the top, a plurality of rows of air holes in said side wall, a centrally apertured ring in said pot above some of said air holes, means to support said ring, a fire-control member mounted in the aperture of said ring and having a collar portion depending therebelow, said collar portion being provided with ports below said ring and with an opening at the top, said control member being provided with a transverse bottom extending across said collar portion, said transverse bottom being provided with an aperture therethrough and a reflecting means overlying said aperture and positioned to reflect heat on oil flowing into said pot, said member wall being outwardly flanged to rest upon said ring, and means to supply oil to said pot.

5. An oil burner comprising a pot having a bottom and an enclosing side wall open at the top, a plurality of rows of air holes in said side wall, a centrally apertured ring in said pot above some of said air holes, means to support said ring, a fire-control member mounted in the aperture of said ring and having a collar portion depending therebelow, said collar portion being provided with ports below said ring and with an opening at the top, a shielding member comprising a top portion located above and spaced from said control member, said top portion being provided with ports extending therethrough and deflectors overlying said ports, and means to supply oil to said pot.

6. An oil burner comprising a pot having a bottom and an enclosing side wall open at the top, a plurality of rows of air holes in said side wall, a centrally apertured ring in said pot above some of said air holes, means to support said ring, a fire-control member mounted in the aperture of said ring and having a collar portion depending therebelow, said collar portion being provided with ports below said ring and with an opening at the top, a shielding member comprising a top portion located above and spaced from said control member, said top portion being provided with ports extending therethrough and deflectors overlying said ports, said deflectors being directed upwardly and outwardly to direct gases flowing through said ports toward the side wall of said pot, and means to supply oil to said pot.

7. An oil burner comprising a pot having a bottom and an enclosing side wall open at the top and a plurality of rows of air holes in said side wall, a centrally apertured ring in said pot above some of said air holes, means to support said ring, a fire-control member mounted in the aperture of said ring and having a collar portion depending therebelow, said collar portion being provided with ports below said ring and a transverse bottom being open at the top, a shielding member comprising a top plate located above and spaced from said control member, said plate being provided with segmental portions bent upwardly and

inclined outwardly to form underlying ports, said ports being shielded by said upwardly bent portions and means to supply oil to said pot.

8. An oil burner comprising a pot having a bottom and an enclosing side wall open at the top and a plurality of rows of air holes in said side wall, a centrally apertured ring in said pot above some of said air holes, means to support said ring, a fire-control member mounted in the aperture of said ring and having a collar portion 10 depending therebelow, said collar portion being provided with ports below said ring and a transverse bottom being open at the top, a shielding member comprising a top plate located above and spaced from said control member, said plate being provided with segmental portions bent upwardly and inclined outwardly to form underlying ports, said ports being shielded by said upwardly bent portions, said plate being provided with supporting and locating means, and means 20 to supply oil to said pot.

9. An oil burner comprising a pot having a bottom and an enclosing side wall open at the top and a plurality of rows of air holes in said side wall, a centrally apertured ring in said pot above 25 some of said air holes, means to support said ring, a fire-control member mounted in the aperture of said ring and having a collar portion depending therebelow, said collar portion being provided with ports below said ring and a transverse bottom being open at the top, a shielding member comprising a top plate located above and spaced from said control member, said plate being provided with segmental portions bent upwardly and 30 inclined outwardly to form underlying ports, said ports being shielded by said upwardly bent portions, said plate being provided with depending legs and means carried thereby to engage said ring whereby said plate is properly positioned

with respect to said control member and ring, and means to supply oil to said pot.

10. An article of manufacture comprising a fire-control device having a collar means associated therewith for support upon the fire ring of a pot type oil burner, said collar being provided with ports therethrough, and a transverse apertured bottom plate, said bottom plate being further provided with an inclined reflector and an aperture therebeneath.

11. A fire-control device for oil burners comprising a member having an apertured collar portion and a transverse bottom plate, a shielding member of plate-like construction superimposed upon said member in spaced relation thereto and provided with ports therethrough and deflector members overlying said ports.

12. A fire-control device for oil burners comprising a member having an apertured collar portion and a transverse bottom plate, a shielding member of plate-like construction superimposed upon said member in spaced relation thereto and provided with ports therethrough and deflector members overlying said ports, said shielding member and said control member being provided with aligned apertures.
